UNITED STATES PATENT OFFICE.

LAURENCE E. TOPHAM, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,250,389.

Specification of Letters Patent. Patented Dec. 18, 1917.

Application filed November 6, 1915. Serial No. 59,963.

To all whom it may concern:

Be it known that I, LAURENCE E. TOPHAM, a citizen of the United States, residing at Swampscott, in the county of Essex and State 5 of Massachusetts, have invented certain new and useful Improvements in Sewing-Machines; and I do hereby declare the following to be a full, clear, and exact description of the invention, such as will enable others 10 skilled in the art to which it appertains to make and use the same.

The present invention relates to sewing machines and more particularly to mechanism embodied in such machines for actuating 15 the awl or needle.

The present invention is applied particularly to a sewing machine of the type shown and described in the patent to Topham No. 1,170,022, dated February 1, 1916. This machine 20 comprises a straight needle and awl, and coöperating instrumentalities constructed and operating to form a lockstitch. In this type of machine the awl is first depressed to enter the work and is then moved laterally to feed the work across a stationary 25 work support. During the continuation of the feed movement the pressure of the work upon the support tends to increase, causing the work to bind unless provision is made 30 for relieving the pressure.

One object of the present invention is to actuate the awl in a path which shall insure the proper feeding of the work without causing an undue pressure of the work against 35 the support during the continuation of the feeding movement. A further object of the invention is to provide an improved form of actuating mechanism for the awl which is simple and efficient in its construction and 40 which may be operated efficiently at the high rate of speed essential in machines of this type.

With the above objects in view a feature of the invention consists in the provision in a 45 sewing machine having an awl and needle, of actuating mechanism for the awl including a rock shaft, a continuously rotated crank, a link operatively connecting the rock shaft and crank, and a cam acting on the 50 link to modify the movement imparted by the rotating crank.

It will be understood that although the preferred embodiment of the invention contemplates the provision of mechanism for 55 actuating the awl, certain features of the

mechanism in their broader aspects may be advantageously embodied in needle actuating mechanism.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 is a front elevation of a machine embodying the features of the invention in their preferred form; Fig. 2 is a vertical 60 sectional view of a portion of the mechanism; Fig. 3 is a detail illustrating a plan view of the awl feed mechanism; Fig. 4 is a side elevation partly in section of the mechanism shown in Fig. 3; Fig. 5 is a cross 65 section taken upon the line 5—5 of Fig. 4; and Fig. 6 is a diagrammatic view illustrating graphically in full lines the paths of the 70 needle and awl according to the present invention and in dotted lines the paths of the 75 needle and awl in the machine illustrated in the application above referred to.

The machine shown in the illustrated embodiment of the invention comprises an awl 1, a straight needle 2, a presser foot 3, a 80 work support 4 having the usual slotted throat plate, a looper 5, a thread finger 6, and a rotary hook 7, all constructed and operating in the usual manner to form a lockstitch as clearly described in the application 85 above referred to. In this type of machine the awl is depressed into operative engagement with the work and is then actuated to feed the work the requisite distance across the work support after which the awl 90 is retracted to disengage it from the work. The awl is conveniently secured to the lower end of an awl bar 10 which is slidingly supported in a carrier 12 hung from parallel supporting links 13 and 14. The link 13 is 95 connected with the usual actuating mechanism to impart a lateral movement to the carrier and cause the awl to feed the work. The vertical position of the awl is determined by the position of the awl bar independently of the vertical position of the carrier. To this end the awl bar is connected through a link 15 to a rocker arm 16 secured to the end of a rock shaft 17 journaled in the 100 machine frame. The rock shaft is oscillated 105 through a link 18 secured to the carrier 12.

from a continuously rotated crank shaft 19 through a crank pin 20 secured to the rock shaft and a link 21 operatively connecting the rock shaft 17 with the crank shaft 19.

5 In the machine described in the application above referred to the rock shaft for the awl is operated directly from the crank shaft through the link 21 to cause the awl to descend into engagement with the work, to

10 remain in its depressed position during the feeding movement, and to finally elevate the awl out of engagement with the work at the completion of the feeding movement. With this construction the elevation of the awl with relation to the work support, as shown clearly in Fig. 6 of the drawings, is substantially the same at the commencement and termination of the feeding movement. The awl in piercing the work compresses it

15 and thereafter the work tends to expand, causing it to bind upon the work support during the continuation of the feed movement. In order to obviate the binding of the work the present invention contemplates the gradual elevation of the awl during the feeding movement to relieve the pressure of the work upon the support without disengaging the awl from the work. As shown clearly in Fig. 6, the path of the awl is inclined slightly to the surface of the work support extending gradually from the lowest position at the commencement of the feeding movement to a slightly elevated position at the completion of the feeding

20 movement. In order to cause the movement of the awl in the above described path while retaining the mechanical advantages of the crank actuated mechanism a cam is arranged to act on the connecting link to modify the action of the crank and the consequent path of movement of the awl imparted thereby. To this end, as shown clearly in Figs. 3 and 4, the link 21 is connected with a crank pin 26 through a slide block 27 carried by the

25 crank pin and moving in a longitudinal slot 28 formed in the end of the link. The crank pin is secured in the enlarged end of a second crank 25. With this construction the effective length of the crank for operating

30 the link 21 is formed by the off-set of the crank 26 from the shaft 19. The movement of the link 21 is modified by a cam 24 rigidly mounted upon the outer end of the crank 25 and having the periphery embraced by oppositely disposed flanges 29 and 30 formed

35 upon the end of the link 21, as shown clearly in Fig. 3. With this construction the oscillatory movement imparted to the link 21 by the crank pin 26 is modified by

40 the cam 24 to impart the proper vertical movements to the awl. A further advantage in connection with the improved type of awl

actuating mechanism may be noted from an inspection of Fig. 6. With the present construction the awl at the completion of the feeding movement is retracted more rapidly than with the simple crank operated mechanism, permitting the earlier advance of the needle through the work and in consequence affording more time for other portions of the cycle of stitch forming operations.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is;—

1. A sewing machine comprising an awl, a needle, a work support, and actuating mechanism for the awl including a continuously rotated crank and a cam for modifying the movements imparted to the awl by the crank during the feeding movement.

2. A sewing machine comprising stitch forming instrumentalities including a needle and awl and actuating mechanism for one of the instrumentalities including a rock shaft, a continuously rotated crank, a link operatively connecting the rock shaft and crank, and a cam acting on the link to modify the movement imparted to the link by the crank.

3. A sewing machine comprising an awl, a rock shaft, connections between the awl and rock shaft, a continuously rotated crank, a link operatively connecting the rock shaft and crank, and a cam connected to the crank and acting on the link for modifying the movement imparted to the link by the crank.

4. A sewing machine comprising an awl, a rock shaft, connections between the awl and rock shaft, a continuously rotated crank, a cam connected to the crank, a link connected with the rock shaft and having a slotted end, a slide block secured to the crank and received in the slotted end, and a pair of oppositely disposed flanges secured to the link and embracing the periphery of the cam.

5. A sewing machine comprising an awl carrier, an awl bar slidingly supported in the carrier, an awl secured to the bar, a pair of parallel links supporting the carrier, means for oscillating the links to move the carrier laterally, a rock shaft connected to the awl bar, a continuously rotated crank shaft, a link connecting the crank shaft and rock shaft, and a cam acting on the link to modify the motion imparted by the crank.

LAURENCE E. TOPHAM.
